LEROY C. DOANE, OF MERIDEN, CONNECTICUT, ASSIGNOR TO THE MILLER COMPANY, OF MERIDEN, CONNECTICUT, A CORPORATION OF CONNECTICUT

SHADE HOLDER

Application filed April 13, 1928. Serial No. 269,651.

The present invention relates to shade holders and is more particularly directed toward a screwless holder suitable for supporting shades.

5 The present invention relates to a shade holder which is exceedingly simple in construction, it being in its preferable form, made out of two simple stampings and three pieces of bent wire so arranged and constructed that resilient wire fingers are supported by one of the stampings and actuated by the other stamping to engage or disengage a shade.

10 The invention also contemplates a shade holder of the above nature wherein the final assembly of the parts may be accomplished without the use of tools, and wherein the spring fingers hold one ring on the other ring.

15 20 The accompanying drawings show, for purposes of illustrating the present invention, one of the many possible embodiments in which it may take form, it being understood that the drawings are illustrative of the invention rather than limiting the same.

In these drawings:

Figure 1 is a side elevational view with parts in section, illustrating the present form of shade holder supporting a shade;

25 30 Figure 2 is a sectional view taken along the line 2--2 of Figure 1; and

Figure 3 is a perspective view showing the parts separated.

Where the shade holder is intended for use 35 with hanging or drop lights, it may conveniently include a stamping 10 in the form of a downwardly opening socket cover adapted to receive the lamp socket. Other forms and shapes may of course be used depending on

40 the conditions to be satisfied. The lower end of the shade supporting stamping 10 is provided with a skirt 11 somewhat larger in diameter than the heel 12 of the shade which is to be supported in it. For convenience, this

45 50 may be considered a fixed ring. The ring or skirt 11 is provided, as here shown, with three long horizontal slots 13, 14 and 15 and with three holes 16, 17 and 18 placed between the slots.

Bent wire shade engaging fingers 19, 20

and 21 are secured to the stamping 10. These bent wire members have anchored ends 22 which are inside the bead 23 on the lower edge of the skirt of the stamping. The wire members are bent upwardly as indicated at 24 to pass through the corresponding holes 16, 17 and 18 in the stamping and are then carried across the inside of the skirt out through the long slots 13, 14 and 15 as indicated. The tips of these wire members are bent as indicated at 26. These wire members are long enough so that they at all times project through corresponding slots and the inwardly bent tips are adapted to be brought in adjacent to the ring or skirt of the stamping when the parts are in the full line position indicated in Figure 2. These wire members, however, are resilient and are biased toward the dot and dash line position shown in Figure 2.

55 60 65 70 75 A revolvable actuating ring 30 also in the form of a sheet metal stamping is placed outside the fixed ring. It has a circumferential bead 31 and a top flange 32. The bead portion of this stamping is provided with three short slots 33. The stamped ring 30 is made of just the proper size to fit outside the skirt of the stamping 10. This stamped ring may be manually inserted in place by passing the ring down over the projecting tips of two 80 85 90 of the spring fingers after which these fingers may be compressed and the third finger forced inside the ring. The spring fingers will be urged outwardly so that the tips of the fingers will ride in the bead or groove 31.

When the ring 31 is turned to the left as indicated by the arrows in Figure 3, the tips of the spring members will be held in this groove, and the members will be held in the inner position; as indicated in Figures 1 and 2, so as to engage underneath the heel or bead 12 of the shade. When, however, the ring is turned in the opposite direction, the tips 26 of the spring members will pass out through the holes 33 in the ring so that these springs 95 will be opened up to the dot and dash line position indicated in Figure 2 thereby releasing the shade so that it can be removed.

100 It will be noted that these operations were carried out without the use of any tools what-

ever and that the shade is securely supported at all times. The ring 30 is securely held in place by the springs. The spring fingers prevent unintentional moving of the ring upwardly or away from the skirt of the socket cover, and it is not large enough to pass down below the bead 23. The device is exceedingly simple in operation and construction and will securely hold small shades. The 10 operations necessary for releasing a shade or for inserting a shade are obvious from a mere inspection of the device so that the user will experience no difficulty in removing or replacing shades when using this form of shade holder.

15 It is obvious that the invention may be embodied in many forms and constructions within the scope of the claims, and I wish it to be understood that the particular form shown is but one of the many forms. Various modifications and changes being possible, I do not otherwise limit myself in any way with respect thereto.

I claim:

20 1. A shade holder comprising a fixed inner ring carrying a plurality of spring fingers attached at one end to the ring, each having a movable end passing through a slot in the ring, and an outer ring engaging with the 25 ends of the fingers to hold them in a predetermined position in the slots for gripping a shade, said ring being movable to another position to permit the spring fingers to expand and release the shade, the outer ring 30 having a circular groove to receive the ends of the spring fingers and permit complete rotation of the outer ring, the ends of the 35 fingers then actuating to hold the outer ring on the inner ring.

40 2. A shade holder comprising a fixed inner ring carrying a plurality of spring fingers attached at one end to the ring, each having a movable end passing through a slot in the ring, and an outer ring engaging with the 45 ends of the fingers to hold them in a predetermined position in the slots for gripping a shade, said ring being movable to another position to permit the spring fingers to expand and release the shade, the outer ring 50 having a circular groove to receive the ends of the spring fingers and permit complete rotation of the outer ring, the ends of the fingers then actuating to hold the outer ring on the inner ring, the groove being cut away to 55 permit the ends of the fingers to project out through the ring when in certain positions.

60 3. In a shade holder, a fixed ring having a plurality of regularly spaced long horizontal slots, a bead about the lower edge of the ring, 65 a plurality of wire spring members each having an end anchored in the bead, each wire member passing through a hole between adjacent slots and extending out through a slot, the free end of the finger being beyond the 70 slot, and a revolvable outer ring movable to

positions where the fingers are all bent in to grip a shade, or where all the fingers are allowed to expand to release the shade.

75 4. A shade holder comprising a circular ring having long horizontal slots, spring fingers each anchored to the ring and having a free portion extending from a point between the slots across the inside of the ring and through a slot to project outside the ring, the end of the finger extending beyond the end of the slot so that the finger is confined in the slot, and an outer revolvable ring adapted to receive the ends of the spring fingers and when turned in one direction to hold them bent inwardly to engage a shade, the ring 80 having holes through which the ends of the fingers may pass when the ring is turned backward, the outer ring also having a circular groove to receive the ends of the fingers and permit complete rotation of the outer ring, the fingers holding the outer ring on the 85 inner ring.

90 5. A shade holder comprising a fixed stamping having a skirt portion adapted to receive the heel of a shade, provided with long horizontal slots and having an external bead about its lower edge, shade engaging wire members each having an end anchored in the bead, the wire members passing inwardly through a hole in the skirt of the stamping, the free ends of the wire members projecting outwardly through the slots, and an actuating ring revolvably carried by the skirt, the ring 95 having a bead to receive the free ends of the wire members and hold them closely in against the skirt when the ring is turned in one direction, the ring also having apertures through which the ends of the members may pass when the ring is turned in the opposite direction to permit the wire members to 100 spread and release the shade.

Signed at Meriden, in the county of New Haven and State of Connecticut, this 11th day of April, 1928.

LEROY C. DOANE.
